LINED DISPLAY BOX AND METHOD OF PACKAGING THEREIN

Robert Morris Bergstein, Cincinnati, Ohio

Application April 7, 1938, Serial No. 200,720

11 Claims. (Cl. 229—14)

In my Patent Number 2,099,257, and in my copending application Serial No. 62,324, I have disclosed containers comprising a multiple wall outer carton, with an inner liner therein, such 5 container being adapted to the reception of contents into the open mouth of the liner, at least at one end of the container. My present invention as herein disclosed constitutes an improvement over these containers, and also is adaptable 10 to other types of lined containers, whether assembled in knocked-down or erect form. By my invention I am enabled to fill contents into the open mouth of a liner in a container, said open mouth being located at one end of the container, but to display the contents by lifting a side or a 15 portion of a side of the container after it has been packed and closed, without disrupting the liner. At the same time I arrange to keep the liner stretched tightly and smoothly over the 20 opening in the side, so provided, so as to present the contents attractively without exposing the contents, and I have also provided an arrangement whereby the side or portion of the side so raised and folded back into display position, is 25 held in display position by the liner itself. Further, as an alternative arrangement I may provide a construction whereby the side so raised is folded around and down under the package, folding therewith also a portion of another side 30 of the outer carton, the parts so folded arranged to be secured under the container to serve as an easel to hold the container in an attractive display position, all without disrupting the liner itself. Further, when it is desired to remove the 35 contents by opening the liner itself, this operation is greatly facilitated by my invention because of the larger area made available for removal of the contents, than is possible to achieve by removing the contents through the end of the package where the contents have been inserted, and 40 my invention also provides a reclosure feature, and by my invention I may also provide a tubular liner wherein the ends of the liner are merely folded in to overlap relation, and not secured, whereby removal through the open side of the outer carton is greatly facilitated. These and other objects of my invention will appear in the 45 description and the drawings forming part of this specification, and the scope and nature of the invention will be set forth in the claims which follow, to which reference is hereby made.

In the drawings:

Figure 1 illustrates the form of my preferred carton structure, as a flat blank, prior to the in-

corporation of the pre-formed tubular liner therein, the shaded areas indicating the portions that are to be adhered to the inner liner.

Fig. 2 shows the completed container, with the inner liner therein, in flat or knocked-down form, 5 in which form it may be shipped to the user.

Fig. 3 illustrates the container shown in Fig. 2 after it has been squared up, and closed at one end, the other end being open and the open mouth of the liner adapted to reception of the contents 10 to be packed therein.

Fig. 4 shows the finished, packed container, contents having been inserted and the other end having been closed. In this condition the container is adapted for shipment. 15

Fig. 5 illustrates the above container with a portion of the side panel having been raised.

Fig. 6 illustrates the container shown in Fig. 5, the lid being folded back to form a display, the tuck on this lid portion being secured behind the liner as indicated in the drawings, to hold the lid in this folded upright display position. 20

Fig. 6a is a section taken along line 6a—6a of Fig. 6.

Fig. 7 illustrates an alternative form of the 25 container illustrated above, the lines of severance of the lid portion being continued around the adjoining side panel as well, and the liner secured in position without adhering the liner to 30 this adjoining side panel, whereby, as shown in the succeeding illustration, the lid panel and the portion of the adjoining panel may be folded away from the container itself, without disrupting in any manner the inner liner.

Fig. 8 illustrates the container shown in Figure 7 with the lid portion of the two side panels referred to folded under the container and the tuck inserted into a slot provided in the succeeding panel, whereby the entire lid portion, that is the portion that has been lifted away from the 35 two panels, serves as an easel, as illustrated, thereby tilting the container in an attractive 40 tilted position for display purposes.

Fig. 8a is a section along line 8a—8a of Fig. 8. 45

Fig. 9 illustrates an alternate construction, wherein the glue seam of the carton is adhered to the outer surface of the panel it overlies, and the flaps articulated to the lid panel are connected to the lid panel by lines of severance. 50

Fig. 9a is a plan view, reduced in scale, of the blank for the box of Fig. 9.

Fig. 10 illustrates the container shown in Fig. 9 after it has been erected and filled with contents and the ends closed, in the same manner as de- 55

scribed with the container shown in Fig. 2 above.

Fig. 11 illustrates the container in Fig. 10 after the glue flap has been released from the panel it overlies by the insertion of a pencil or other sharp object which is pushed along between the two overlapped panels to separate the glue seam. The lid panel has thereupon been raised along the lines of severance provided therefor, exposing thereby a complete side, without disrupting the liner itself.

Fig. 12 illustrates another alternate construction, wherein medial fold lines are provided on two opposite panels, by which the carton is folded in flat or knocked-down form, the inner liner being closed independently at one end of the container. The lid arrangement is similar to that shown in Figure 9, except that the lines of severance in this illustration are located as shown, so that the lid which can be raised is only a portion of one panel, and not the complete panel itself as illustrated in Fig. 9.

Fig. 13 illustrates a lined carton which has been assembled in erect form, the carton itself being made according to my preferred construction as illustrated in Fig. 1, squared up into erect form and one end closed prior to the introduction of the inner liner. Prior to the introduction of the inner liner within the outer carton, adhesive has been provided to secure the liner to the carton at the desired surfaces, but provided so as not to interfere with the subsequent raising of the lid panel on the side.

For the sake of clarity in referring to the drawings, we will refer to the sides or main body panels of the outer carton, simply as "panels" and consider that portion of the sides of the outer carton which is to be raised, as the "lid panel" whether this portion adapted to be lifted comprises merely a portion of one of the panels, the entire panel, or more than a single panel, as is the case in Fig. 5. The flap provided on the carton to retain the carton in tubular form, by gluing or otherwise, will be referred to as the "glue flap" and the end flaps articulated to the panels for enclosing the end of the container will be referred to as the "closing flaps". The blank shown in Fig. 1 has four panels 1, 2, 3, and 4, there being transverse lines of severance 5, 5 in panel 4, the portion of this panel between the lines of severance serving as the lid panel. As can be noted, these lines of severance continue through the glue flap 6, and in this case the lid panel has been provided with suitable lines of cut 7 and fold 8, to provide a suitable design for subsequent folding back into display position, while if the lid is to serve merely as a means for subsequently opening the container to remove the contents, and not for display purposes, the lines of cut and fold in this lid panel could be omitted.

The shaded portions 9 indicate the areas of the inner surface of the carton which are to be adhered to the pre-formed liner. It will be noted that no adhesive is provided on the inner surface of the lid panels, or on the inner surface of the portions of the glue flap which are articulated to the lid panel.

Fig. 2 shows the blank illustrated in Fig. 1 after the preformed liner has been introduced, and the carton has been folded and secured about the liner. It should be noted that the portion of the glue flap which is articulated to the lid panel is not adhered to the panel 1 which overlies it, but the adjoining portions of the glue flap have been so adhered to said panel 1, thereby

serving to hold the carton in tubular form. When the carton has been so folded about the inner liner, the liner 10 will be adhered to the inner surfaces of the carton along the shaded areas shown in Fig. 1. In this particular illustration the inner liner is a flexible pre-formed tube, with the overlapping portions indicated at 11, not adhered to each other. However, when the inner liner has been so folded and placed within the outer carton, it will retain its tubular condition, but the absence of adhesion between the overlapped portions of the liner serves to simplify the opening of the liner from the side after the lid panel has been lifted subsequently. It will be noted from the drawings that the overlapped portion of the liner is placed so as to face upwardly, that is to appear in the opening exposed on the side of the carton when the lid panel has been lifted. In instances where a sealing of the liner is desired, the lengthwise seam will be sealed before introduction of the tube and it may also be desirable to seal one end of the tube forming a flat bag for securing within the carton. Materials which are transparent and still highly impermeable are available for such liners.

In this particular illustration the container is designed to be closed by inter-folding the ends of the liner and the closing flaps.

Figure 3 illustrates the container after the carton has been squared up into erected form, and one end so closed. In closing this end, the closing flaps 12 and 13 are first folded inwardly, serving to fold in a corresponding portion of the open end of the liner with them, and the closing flaps Nos. 14 and 15, are folded into overlapping relation. The flaps may be secured by adhesion, or by locking, or by any one of a number of well-known means.

It should be noted from the illustration that I prefer to have the end of the liner extending beyond the end of the closing flaps which are the first mentioned flaps just referred to. In this manner when these flaps are folded in, the liner will cover the edges or ends of same on the interior of the container, so that no portion of the outer carton itself is in contact with the contents. When the contents are of a greasy nature for example, such as doughnuts, this feature is of importance because the liner may be made of grease-proof material such as glassine or Cellophane or the like, whereas the outer carton may be cardboard or other material which is not grease-resistant, so it is important that the contents come in contact with the liner only, and not with the outer carton.

After one end has been closed as shown in Fig. 3, the container is ready for filling through the other end of the container, the contents being introduced of course through the open mouth of the liner, and after the contents have been introduced and the contents filled, this end may be closed in the same manner as the end just described was closed. The container is now in the form illustrated in Fig. 4, which form provides a package, the contents being held within the inner liner, and the inner liner being adequately secured to the outer carton so that it is held from shifting, etc., and in this condition the manufacturer of food products or the like can ship the package.

Fig. 5 shows the package illustrated in 4, but with the lid raised. Since the portion of the glue flap which is articulated to the lid panel has not been adhesively secured in position, it

is extremely simple to lift this lid panel, and the lines of severance 5 can either be complete cuts through the carton itself, or may be lines of perforation or the like. It can also be seen that the lifting of this lid panel in no way disrupts the inner liner, and the liner is held securely in taut position over the opening, providing a neat and attractive appearance, and providing full protection for the contents.

As shown in Fig. 6, this lid panel may be folded back into display position, the portion of the glue flap articulated to the lid panel serving as a tuck, this tuck being placed between the liner and the panel 3. It should be noted that the liner has been left unsecured to the upper part of panel 3, to provide clearance space for the tuck in this case. This serves to retain the lid panel folded back into display position, providing as can readily be seen, an attractive box for the merchant or retailer to place upon the counter, with excellent display value, and at the same time with the contents protected by the inner liner so as not to be exposed and still receive the full benefit of whatever protective qualities which are provided by the inner liner.

In the modification shown in Figs. 7 and 8, the lines of severance in the lid panel have been continued into panel 3 as at 5a. In this case the liner is so glued to the carton that the portion of the lid panel formed from the panel 3, is unsecured to the liner, whereby as shown in Fig. 8 the lid panel, comprising parts of both panels 4 and 3, can be folded back around under the carton, without disrupting the inner liner in any way. As also illustrated a slot 16 has been provided in panel 2, in which the tuck may be inserted, so that the lid panel which has been folded around and under the package serves as an easel, giving the package a tilt providing an attractive and effective unit on the counter, and here again this has been accomplished without disrupting the inner liner.

In the alternate construction shown in Fig. 9, the entire glue flap 6 has been secured to the panel 1, which it overlies, and in this embodiment it should be noted that the glue flap overlies rather than underlies the panel referred to. In this construction as illustrated, the glue flap has been increased somewhat in width over that actually required to make an effective seam, the reason for this being that the glue seam itself can be confined to a relatively limited area as illustrated at 17, making it simple for the user or dealer to insert a pencil or other sharp pointed object and rip through this glue seam, thereby freeing the glue flap from the panel to which it was secured. Thereafter if desired to reclose the lid, the glue flap can then serve as a tuck for the lid panel. In this particular embodiment also the transverse lines of severance 18 serve to articulate the closing flaps to the lid panel, so that after the glue flap has been released by the seam being broken as just described, the lid panel may be raised to expose the complete side of the container. The liner is secured to the closing flaps along line 19, 19, in this construction so that it is not released when the entire panel 4 is raised.

In Fig. 10, the container in Fig. 9 is shown with the ends sealed, the contents being therein, and Fig. 11 shows this container with the lid raised, as just described.

In Fig. 12 the carton illustrated has intermediate lines of fold 20, in the panels 1 and 3, on which the carton is folded about the inner

liner. The inner tubular liner 21, illustrated is closed at one end as at 22, providing independent closure for the inner liner, instead of the inner liner being interfolded with the flaps as in the previous illustration. The carton is squared up by pressing inwardly on the intermediate lines of fold, and can thereafter be closed at the end adjoining the closed end of the liner by folding in and securing the closing flaps, and after the contents have been introduced the open mouth of the liner can be sealed independently if desired, and the closing flaps at this end folded inwardly, providing a completed squared package in erect form, in which the inner liner is independently sealed. The lid panel arrangement in this embodiment is similar to that shown in Fig. 9, except that instead of an entire panel being utilized, the transverse lines of severance 23 defining the lid panel incorporate only a portion of panel 4, which is an alternate lid arrangement adapted to either the style container shown in Fig. 12, or to the previously described type.

In this form the panel defined by the lines 23 is not adhesively secured to the liner, and the tabs 23a, 23a, are adhesively secured as well as the flap 6, to the outside of the wall 1 of the carton, as shown.

In Fig. 13 the container is formed from a blank as shown in Fig. 1, the blank being folded and glued in tubular form, and thereafter squared up and one end being closed by the closing flaps. Thereafter, an erect or squared up tubular liner, which may have one end closed if desired, is introduced into the erect carton, and adhesive provided so as to secure the liner to the carton, except for the portions of the carton which form the lid panel, and the tuck on the lid panel. Thereafter the container may be filled with contents through the remaining open mouth of the liner, and closed, and subsequently opened with the lid panel, as previously described in connection with Figs. 3, 4, etc. This modification contains only a portion of the advantages of my construction.

It will be noted that my invention provides an extremely efficient and effective method of packaging contents of various sorts, thereafter displaying and dispensing same. The contents are filled into the container through the open mouth of the liner, which open liner mouth is exposed between the closing flaps at one end thereof. Thereafter the liner and the closing flaps at this end are closed, and subsequently the contents may be displayed by lifting the lid panel, which is accomplished without disrupting the liner so that the contents may be displayed without losing in any way the effectiveness of the protective qualities of the inner liner. Upon lifting the lid panel a large liner area is exposed, and if it is desired to open the liner and remove the contents through this exposed area, it is extremely easy to do so, much simpler than it would be were it necessary to remove the contents through the end of the container where they were inserted.

Further, the lid panel provides a very effective closure feature, as for example after being placed on the counter in display position with the liner remaining intact, the lid panel can be again brought into closing position to protect the liner, while for example it is carried from the store to the home, and this same reclosure feature is of importance once the liner has been opened, as the lid panel can be placed into closing position.

securely, as is often desired, during the time when the contents are being consumed.

To achieve the maximum display value, it is obvious that the liner may be made of Cellophane or other transparent sheets, and of course the liner can also be made of any suitable flexible material to provide the desired protective qualities for the contents.

It can be seen that by my invention, I have provided means whereby the container can be opened and reclosed if desired, for display purposes, without disrupting the liner and the contents within the liner can be effectively displayed without exposing the contents, and without causing the contents to lose the benefits of the protective qualities which may be inherent in the liner material.

As pointed out, it is immaterial in my invention herein disclosed whether the liner is interfolded with the flaps of the carton or whether the ends of the liner are closed independently of the closing flaps of the carton. As explained in connection with Fig. 1, I may also if desired, provide a folded pre-formed tubular liner instead of a liner adhered at its tubular seam if desired, in order to facilitate dispensing of the contents. It is obvious also that the liner could be made of several materials combined, for example a Cellophane face at the portion underlying the lid panel, and other material at the portions adjoining other panels. Such modifications can be made without departing from the spirit or scope of my invention, and having thus described my invention what I claim as new and desire to secure by Letters Patent is as follows:

1. A container comprising a multiple panel outer carton having closing flaps at both ends thereof and within said carton a tubular liner having its open mouth projecting intermediate said closing flaps of at least one end of said carton, suitable for reception of contents therein, said liner being secured to the interior surface portions of said carton other than one of said panels, and said panel having transverse lines of severance whereby it can be raised into opening position without disturbing the liner, so that contents may be removed thereafter through said side opening, upon opening the liner.

2. A container comprising an outer carton and a liner therein prepared for introduction of contents from the end through the open mouth of said liner, and removing contents through one of the sides thereof, said side being substantially completely unsecured to said liner and having transverse lines of severance whereby it can be raised without destroying said liner.

3. A method of filling, displaying and dispensing contents in a package which comprises providing a container consisting of an outer carton with closing flaps at the end thereof and within said carton a flexible liner an open mouth of which extends intermediate said closing flaps on at least one end of said carton, and said carton having at least one side panel thereof prepared so as to lift into opening position to serve as a lid panel, the liner being substantially completely unsecured to said panel, comprising inserting contents into the liner through the open mouth thereof, closing the liner mouth and the end flaps about said contents and thereafter lifting said lid panel whereby the contents can be displayed through the liner without disturbing the integrity of the liner and can also be removed subsequently through said side opening, upon opening the liner.

4. A container comprising an outer carton

having closing flaps at both ends thereof and held within said carton a flexible liner, an open mouth of which extends intermediate the closing flaps at one end thereof at least, adapted to reception of contents therein, a side panel of the carton being prepared with transverse lines of severance whereby the portion between said lines may be raised into opening position, said portion being substantially completely unsecured to the liner.

5. As an article of manufacture a container in flat or knock-down form comprising an outer tubular carton of articulated panels having closing flaps at the end thereof and within said carton a pre-folded flexible tubular liner secured to at least two opposite panels of the carton whereby when said carton is squared up said liner will be likewise squared up, and said liner being substantially completely unsecured to at least one side panel of the carton, said panel having transverse lines of severance to be raised into opening position without affecting the liner.

6. As an article of manufacture a container in flat or knock-down form comprising an outer tubular carton of articulated panels retained in tubular form by a glue flap articulated to a panel thereof and having closing flaps at the end thereof and within said carton a pre-folded flexible tubular liner secured to at least two opposite panels of the carton whereby when said carton is squared up said liner will be likewise squared up, the panel to which the glue flap of the carton is articulated having transverse lines of severance whereby when the glue seam retaining said flap is severed said flap and panel may be raised into lid position, the liner being substantially completely unsecured to said flap and panel, and the glue flap serving thereafter as a tuck for said lid panel.

7. A container comprising an outer carton having closing flaps at the ends thereof and one of the panels of which has articulated thereto a glue flap, said glue flap and panel having transverse lines of severance therein, said carton being folded about the inner flexible tubular liner, the portion of the glue flap between the transverse lines of severance being substantially completely unsecured, and the outer portions of the glue flap being secured to the opposite carton panel which is lapped thereby, the liner being adhered to panels of the carton other than said aforementioned panel and intermediate portion of the glue flap, whereby the intermediate panel portion with the glue flap articulated thereto may be lifted to serve as a lid, the glue flap serving as a reclosure tuck thereon.

8. A container comprising an outer carton having closing flaps at the ends thereof and medial lines of fold in two opposite panels, said carton being folded on said medial lines about a flexible tubular liner secured therein, said liner being closed at one end, and said carton being secured to the liner so that when the carton is squared up the liner will likewise be squared up, but a portion at least of one panel of said carton being substantially completely unsecured to the liner, said panel being adapted to raise into open position without disturbing the liner, whereby the liner is exposed under the lid panel and adapted to subsequent removal of contents through said exposed side.

9. A flat folded container comprising a carton having closing flaps and panels forming the walls thereof, and a glue flap on one end panel of the original blank arranged to lap the other end

- panel thereof, said first mentioned panel provided with lines of severance, lying within the ends of said panel and extending through the glue flap, a liner within said carton, said liner adhesively joined to the liner.
5. joined with at least two opposing panels thereof, sufficiently to cause a substantial conformance of said liner to the complete areas of the said panels, the portion of the glue flap which is defined by the lines of severance being unsecured 10 in forming the carton, and the portion of the panel defined by the lines of severance being substantially unsecured to the liner.
10. A flat folded container comprising a carton having closing flaps and panels forming the walls 15 thereof, and a glue flap on one end panel of the original blank arranged to lap the other end panel thereof, said first mentioned panel provided with lines of severance, lying within the ends of said panel and extending through the 20 glue flap, a liner within said carton, said liner adhesively joined with at least two opposing panels thereof, sufficiently to cause a substantial conformance of said liner to the complete areas of the said panels, the portion of the glue flap which 25 is defined by the lines of severance being unsecured in forming the carton, and the portion of the panel defined by the lines of severance being substantially completely unsecured to the liner remaining portions of the panel being adhesively joined to the liner, said liner being unsecured likewise to a portion of the panel adjoining said lid panel, providing a clearance space wherein the unsecured portion of the glue flap may be inserted to retain the lid panel upon being folded back.
11. A flat folded container comprising a carton having closing flaps and panels forming the walls thereof, and a glue flap on one end panel of the original blank arranged to lap the other end panel thereof, said first-mentioned panel provided with lines of severance, lying within the ends of said panel and extending through the 10 glue flap, a liner within said carton, said liner adhesively joined with at least two opposing panels thereof, sufficiently to cause a substantial conformance of said liner to the complete areas of the said panels, the portion of the glue flap 15 which is defined by the lines of severance being unsecured in forming the carton, and the portion of the panel defined by the lines of severance being substantially completely unsecured to the liner remaining portions of the panel being adhesively joined to the liner, said liner being unsecured likewise to a portion of the panel adjoining said lid panel, providing a clearance space wherein the unsecured portion of the glue flap 20 may be inserted to retain the lid panel upon being folded back.

ROBERT MORRIS BERGSTEIN.
